UNITED STATES PATENT OFFICE.

HALSEY C. DE BAUD, OF NEWARK, NEW JERSEY, AND ALBERT C. COUCH,
OF NEW YORK, N. Y.

DESIGN FOR THE ORNAMENTATION OF SKATING-RINKS.

SPECIFICATION forming part of Design No. 15,714, dated January 13, 1885.

Application filed September 12, 1884. Term of patent 7 years.

To all whom it may concern:

Be it known that we, HALSEY C. DE BAUD and ALBERT C. COUCH, citizens of the United States, and residents, respectively, of Newark, 5 Essex county, and State of New Jersey, and New York city, New York county, and State of New York, have invented and produced a new and original Design for Interior Decorations of Skating-Rinks and other Buildings, of which 10 the following is a specification, reference being had to the accompanying drawings, forming part thereof.

Our invention relates to a novel design of 15 interior decoration for skating-rinks and other buildings; and it consists in representations of the various seasons of the year in their natural order, as will be hereinafter more fully explained in connection with the accompanying drawings, forming part of this specification. 20

In the drawings, Figure 1 is a plan view of 25 a skating-rink embodying our novel design of ornamentation or decoration. Fig. 2 is a perspective view showing the arch-sections and delineating decorations representative of the several seasons of the year. Fig. 3 is a longitudinal section of the rink, showing the ceiling and side wall decorations. Figs. 4, 5, 6, 7, 8, 9, 10, 11, 12, and 13 are views of the 30 separate arch-sections. Fig. 14 is a view of an arctic scene.

In the several views the same parts will be found designated by the same letters of reference.

35 A is the skating-rink or building, provided with the usual walls, floor, and roof, which latter is arch-shaped in cross-section over that portion of the structure devoted to skating purposes. The customary arches used to 40 sustain the main roof of the building are decorated by us to produce within the structure aesthetic effects novel, beautiful, and striking. At the entrance to the building the first arch, 1, we decorate in a manner suggestive of early 45 spring and the month of April by depicting foliage thereon. The next arch, 2, is decorated to represent the month of May and a more advanced stage of the spring season by ornamentations of blossom foliage. The succeeding three arches, 3, 4, and 5, are appropriated

by the summer season, and are decorated by 55 tropical or other scenes suggestive of the months of June, July, and August. The following three arches, 6, 7, and 8, are employed to illustrate the autumn season, and scenes familiar to the months of September, October, and November are successively portrayed thereon, graduated from withering leaves to bare branches of trees. The next arches, 9 and 10, are 60 used to exhibit the season of winter, and are decorated with a becoming scene, as of icicles, snow, &c., usual during the month of December and the winter season.

From the foregoing description, taken in 70 connection with the accompanying drawings, it will be observed that we have scenic decorations on the arches supporting the roof of the building representative of the various seasons of the year, (and the various months of the seasons,) beginning with spring-time, and 75 following along in natural order to winter. Beyond the arch 10, near the further end of the building, we show scenery imitative of icebergs and the arctic regions, as at a, and on the end wall we present a picture of the 80 aurora borealis or northern lights, or other luminous polar phenomenon, as at b. Along the side walls and ceiling of the structure, and between the various arches 1, 2, 3, &c., are also depicted scenes or decorations in agreement with those on the arches, and which also graduate naturally from spring-time to winter, and to arctic scenes, in a manner similar to those on the arches. So, too, along the floor 85 of the building and between the various arches are trees, flowers, plants, &c., either natural or artificial, and scenery to represent the winter season, all of which progress from end to end of the building in the natural order of the 90 seasons, and in a like manner to the decorations of the arches.

It will be seen that by our novel design of 95 interior decoration are presented to the eye all over the structure—on the arches, the ceiling, the walls, and the floor—scenes representing the several seasons of the year, all in their natural order, and harmoniously progressing from early spring to frosty winter, and one traversing the building from end to end will have presented to his vision, step by step, surround- 100

ings indicative of the four seasons of the year and of the various stages of such seasons, the whole effect of which is one of actual grandeur.

What we claim as new, and desire to secure by design Letters Patent, is—

1. The design for a skating-rink or other building herein shown and described, the same consisting of the interior decorations, representing at 1 and 2 the season of spring, at 3, 4, and 5 the season of summer, at 6, 7, and 8 the season of autumn, and at 9 and 10 the season of winter.

2. The design for a skating-rink or other building herein shown and described, the same

consisting of the interior decorations representing at 1 and 2 the season of spring, at 3, 4, and 5 the season of summer, at 6, 7, and 8 the season of autumn, at 9 and 10 the season of winter, and at *a* and *b* the arctic or polar regions.

In witness whereof we have hereunto set our hands.

HALSEY C. DE BAUD.
ALBERT C. COUCH.

In presence of—

JACOB FELBEL,
F. H. JONES.
